in which an inked cell is later recovered by dipping the entire frame 11 into water. A part of the design is shown across 10, part of the frame 11 being shown in detail. The original has several other designs and the design need not be similar to that shown.

UNITED STATES PATENT OFFICE

Patent No. 2,329,493, issued Sept. 14, 1943, to Claude D. Tilson, Manchester, N. H., for a marking machine.

MARKING MACHINE

Claude D. Tilson, Manchester, N. H., assignor of one-half to North American Holding Corporation, Syracuse, N. Y., a corporation of New York, and one-half to Parshad Holding Corporation, Syracuse, N. Y., a corporation of New York

Application October 2, 1940, Serial No. 359,323

1 Claim. (Cl. 101—301)

This invention relates to an improvement in a marking machine, more particularly one of the type shown in the patent to Edwards, No. 1,753,884, dated April 8, 1930, wherein a design is imprinted upon a section of a shoe upper or similar piece of sheet material by a marking plate or die supported upon a reciprocably mounted platen.

The primary object of this invention resides in the provision of an ink supply means by which the die is supplied with ink, such means including a die contacting element movable intermittently by and in timed relation to the reciprocation of the die carrying platen.

Another object of the invention resides in the structure of the supporting means for the die carrying platen and the connection between such supporting means and the die contacting element of the ink supply means.

These and other objects of the invention will appear from a consideration of the following description and of the drawings which form a part thereof and in which

Figs. 1 and 2 together illustrate in side elevation a machine embodying this invention;

Fig. 3 is a sectional plan view thereof taken along the line 3—3 in Fig. 1;

Fig. 4 is a longitudinal sectional view taken along the line 4—4 in Fig. 3;

Fig. 5 is a transverse sectional view taken along the line 5—5 in Fig. 3;

Fig. 6 is a plan view of the means by which the die contacting element of the ink supply means is actuated; and

Fig. 7 is a side elevation of such means.

The marking machine 10 illustrated in the drawings is particularly adapted to imprint designs, guide lines and the like upon sections of shoe uppers, and comprises briefly three units, viz., a bed 20 on which the sections of the shoe uppers are supported when being so imprinted, a platen 30 by which the marking die 40 is carried, and an ink supply means 50. These units are supported by a rectangular base frame 11 which rests upon a table 12.

The bed 20, here shown as an integral part of the frame 11, carries a mat 21 which is positioned on the bed by pins 22 which project upwardly from the bed through apertures in the mat, and by a leaf 23 fixed to the bed and projecting outwardly therefrom. On edge of the mat abuts an edge of the leaf and straps 24 pivotally mounted on the leaf extend over the mat and prevent any inadvertent raising thereof. A gauge 25 attached to the mat 21 in any desired manner as by cement

and adhesive is used to indicate the height of the platen 30 above the bed 20.

The platen 30 is supported by a base frame 11.

The base frame 11 is supported by a base 12.

The base 12 is supported by a base frame 11.

The base frame 11 is supported by a base 12.

The base 12 is supported by a base frame 11.

The base frame 11 is supported by a base 12.

The base 12 is supported by a

of the roller 55 is a sheave 65 to which one end of a cable 66 is secured and about which that end is wound. A coiled spring 67 is secured at one end to one of the arms 61 and at the other end to the sheave and holds the latter normally at rest. A ratchet wheel 68 is carried by the roller 55 and its teeth are engaged by a pawl 69 on the sheave 65 held by a spring 70 in contact with the teeth. The other end of the cable 66 is secured to a pin 71 carried by one of the rear levers 31 of the platen 30. As shown in Fig. 1, the pin 71 is seated in any one of a plurality of apertures 72 so that the relation of the roller 55 to the levers 31 may be adjusted as desired.

The operation of the above marking machine will be described. It is assumed that the machine elements are in the position shown in full lines in Fig. 1, the die 40 carried by the platen being inked and a shoe upper section being on the bed 20 in position to receive the imprint of the die. The platen is swung to the left either by depressing the treadle 45 or by means of the handle 42 until the pattern on the die 40 is printed on the upper section. The platen is then released and the springs 37, which were expanded, retract the platen 30 at such a speed that it is carried past the full line position of Fig. 1 until the die carried thereby rests upon the transfer belt 53.

During this movement of the platen 30, the ink transfer belt has also been advanced through the rotation of the roller 55 by the cable 66, sheave 65, and ratchet 68. As the levers 31 swing to the left, the cable 66 rotates the sheave 65 and ratchet 68 (clockwise in Fig. 1), thus

moving the upper run of the belt to the right in Fig. 1. The spring 67, tensioned thereby, acts when the levers 31 move to the right to rotate the sheave and take up any slack in the cable 66. After the die 40 has been inked by the belt 53 the platen is returned by the springs 37 to the initial position ready for further use. Should it happen, when the machine is to be used, that the ink on the die 40 be dry, it will be reinked by swinging the platen to the right in Fig. 1 until the die contacts the belt.

While one embodiment of this invention has been shown and described, it will be understood that I am not limited thereto and that other embodiments of the invention may be made without departing from the spirit and scope thereof as set forth in the following claim.

I claim:

In a marking machine, a reciprocably mounted platen, levers on which said platen is carried, a die supported by said platen, a bed adapted to support the material to be marked by said die, an ink transfer belt by which ink is supplied to said die, rollers carrying said belt, a sheave rotatably supported upon one of said rollers, a ratchet mounted upon said roller, a pawl on said sheave in mesh with the teeth of said ratchet, a spring attached to said sheave and tensioned by its rotation in one direction, and a cable wound about said sheave and attached to one of said levers, whereby upon the reciprocation of the platen in one direction the sheave is rotated and the pawl thereon acts through the ratchet wheel to rotate the roller and advance the belt.

CLAUDE D. TILSON.
